FISHING ROD HANDLE

David C. McElroy, 9818 Grinnell, Detroit, Mich.

Filed July 21, 1960, Ser. No. 65,407

Term of patent 14 years

(Cl. D31—4)

FIG. 2.

FIG. 1.

FIG. 3.

FIG. 1 is a perspective view of a fishing rod handle embodying my new design.

FIG. 2 is a top plan view thereof.

FIG. 3 is a bottom plan view thereof.

The side not shown is substantially like the side shown.

The dominant features of my design reside in the portions shown in full lines.

On behalf of David C. McElroy, I claim:

The ornamental design for a fishing rod handle, as shown and described.
